UNITED STATES PATENT OFFICE.

LOUIS A. SWINT, OF PICKENS, WEST VIRGINIA.

WRENCH.

1,153,271.

Specification of Letters Patent. Patented Sept. 14, 1915.

Application filed July 8, 1913. Serial No. 777,252.

To all whom it may concern:

Be it known that I, LOUIS A. SWINT, a citizen of the United States, residing at Pickens, in the county of Randolph, State of West Virginia, have invented certain new and useful Improvements in Wrenches; and I do hereby declare the following to be a full, clear, and exact description of the invention, such as will enable others skilled in the art to which it appertains to make and use the same.

This invention relates to wrenches, and it more particularly relates to an improved form of monkey-wrench.

15 An object of the invention is to provide a wrench of this character which may be more quickly and more easily adjusted than is possible with wrenches of ordinary construction.

20 Another object is to provide a wrench of this character, which, when adjusted, positively retains its adjusted position until it is released therefrom by the operator.

Another object is to provide a wrench of 25 this character which is especially easy to adjust.

Another object is to provide a wrench of this character which is strong, compact, comparatively simple of construction, comparatively inexpensive, and thoroughly efficient.

Other objects and advantages may be recited hereinafter and in the claim.

In the accompanying drawings, which supplement this specification: Figure 1 is a 35 side elevation view of my improved wrench. Fig. 2 is a longitudinal sectional view of my improved wrench. Fig. 3 is a longitudinal sectional view through the middle of the wrench, the section being taken at right angles to Fig. 2. Fig. 4 is an enlarged sectional view on the line 4—4 of Fig. 1. Fig. 5 is a side elevation view of the stationary jaw and inner handle member, and Fig. 6 is a perspective view of the movable jaw and 45 intermediate handle member.

Referring to these drawings, in which similar reference characters correspond with similar parts, throughout the several views: the wrench consists of the main frame or 50 base member 10, the movable jaw member 11, outer handle member 12, the limiting pin 13 and the screw bolt 14.

The main base member is formed integrally with the inner handle member 15, 55 this handle member being provided with two oppositely disposed series of laterally ex-

tending ribs or ridges 16 and alternate notches 17, while two other opposite sides of this elongated inner handle member are grooved at 18 for the reception of the ribs 19, hereinafter described. A slot 20 extends from one end portion toward the medial portion of the element 15, and through this slot extends the limiting pin or stop member 13, which also extends through opposite apertures 21 of the intermediate handle member. This handle member may be either formed integrally with or fixedly secured to the movable jaw 22, the latter being apertured at 23, for receiving the inner handle member and being adapted to slide thereon. The intermediate handle member consists of two parallel bars or slides on which the ribs 19 are formed, said ribs being snugly and slidably fitted within the grooves 18, 75 while the convexed surfaces 25 of said bars overlap the plane surfaces 24 and have sliding movement thereon.

A centrally apertured bridge element 26 unites two adjacent end portions of the parallel bars, so that a yoke is formed by said bridge element and said parallel bars. At the junction of this yoke with the movable jaw element 22 is formed a boss 27, provided with shoulders 28; while the handle member 12 is formed with a recess 28', which is enlarged at 29, and this enlargement of the recess is inclosed by a longitudinally extending flange 30 having a thickened portion 31 with shoulders 32 formed 90 at its ends. An aperture 33 extends through the free end of the handle member 12 and communicates with the recess 28', and is adapted to receive the screw bolt 14 which also extends through the central aperture of 95 the element 26 and is provided with a nut with which it coacts for holding the intermediate handle member against longitudinal movement in the outer handle member. The shoulders 32 are adapted to coact with 100 the shoulders 28, so that the rotation of the handle member 12 is limited to approximately ninety degrees.

The inner wall of the hollow handle member 12 is provided with two opposite series 105 of spaced, parallel and laterally disposed ribs 34, which may be slightly inclined to the length of the handle members, or else, these ribs and the ribs 16 may be convergent at one of their respective ends, so that they 110 may be forced into engagement with one another, or into intermeshing relation by

the limited rotation of the handle member 12, as described in the foregoing.

From the foregoing, it will be seen that when the ribs 34 are in mesh with the ribs 16, the jaw members 22 and 22' are locked in fixed relation with each other; but when the said ribs are out of mesh, the inner handle member may be easily slid in either direction with relation to the intermediate handle member and outer handle member, and when the proper adjustment has been obtained, it is only necessary, in order to again lock them in fixed relation, to rotate the handle 12 until the ribs thereof mesh with the ribs of the inner handle member.

It will be seen that the pin 13 extends through the slot 20, for limiting the distance to which the jaws may be separated.

In order that the handle member 12 may be secured in its intermeshed relation with the inner handle member, while the wrench is being used, I may provide any suitable securing means, such, for instance, as a resilient latch plate 36 having a depression 35 formed therewith for engaging the boss 37 in the yoke or inner handle member.

From the foregoing, it will be seen that I have provided a device of this character which is fully capable of attaining the fore-

going objects, in a thoroughly practical and efficient manner.

I do not limit my invention to the exact details of construction, combination and arrangement of parts, as herewith illustrated and described, but my invention may only be limited by a reasonable interpretation of the claim.

What is claimed is:—

A wrench comprising a jaw, a shank portion on said jaw, said shank portion being substantially rectangular in cross section and having longitudinally extending slots on opposite faces thereof, and transversely extending grooves on the other opposite faces thereof, a movable jaw mounted on said shank portion and having extensions slidably mounted in the aforementioned grooves, a handle rotatably mounted on said movable jaw, means for swivelly connecting the said handle to the said extensions, and means for normally preventing the handle from rotating.

In testimony whereof, I affix my signature, in the presence of two witnesses.

LOUIS A. SWINT.

Witnesses:

JNO. L. THOMAS,
MAX STADLER.
